Primary Examiner — Kelley Donnelly*(74) Attorney, Agent, or Firm* — Ryan Kromholz & Manion, S.C.(57) **CLAIM**

The ornamental design for a collapsible structure, as shown and described.

DESCRIPTION

FIG. 1 is a perspective view of a first embodiment;
FIG. 2 is a right side elevation view, the left side elevation view being identical;
FIG. 3 is a front elevation view, the rear elevation view being identical;
FIG. 4 is a top plan view;
FIG. 5 is a bottom plan view;
FIG. 6 is a perspective view of a second embodiment;
FIG. 7 is a right side elevation view, the left side elevation view being identical;
FIG. 8 is a front elevation view, the rear elevation view being identical;
FIG. 9 is a top plan view; and,
FIG. 10 is a bottom plan view.
